RECOIL CONTROL OF FIREARMS

Robert H. S. Hughes, Baltimore, Md., assignor of
one-half to Milton Roberts, Chicago, Ill.

Application January 10, 1936, Serial No. 58,574

5 Claims. (Cl. 89—14)

This invention relates to a device for minimizing recoil in guns which are adapted to fire projectiles. The device comprises a metal body having a gas chamber therein and having a cylindrical bore, adapted to receive the muzzle end of a gun barrel, extending inwardly from the rear end of said device and forming the inlet to the chamber, the forward part of said bore constituting part of said chamber, said device having a seal port at the forward end of the chamber in axial alignment with said cylindrical bore and having an internal shoulder extending laterally from the inner end of the seal port to the side wall of the chamber, which wall flares rearwardly and outwardly from the periphery of said shoulder and closes the forward part of the chamber, adjacent the shoulder, against the lateral escape of gas. The device has a rearwardly facing external shoulder to the rear of the aforesaid shoulder in the chamber and to the rear of the forward end of said cylindrical bore and has a plurality of discharge ports extending rearwardly and outwardly from the chamber in line with said internal shoulder and extending through the external shoulder. When the gun is fired the projectile passes through the chamber and the seal port, and the gases and still burning products of combustion from the gun barrel, entering the chamber, create a very high gas pressure therein, and the gases discharging through the rearwardly and outwardly directed ports against the atmosphere react against the shoulder in the chamber and greatly reduce the recoil. An annular flange on the rear end of the body constitutes a guard which prevents the discharged gases from interfering with the person using the fire arm. To eliminate the flash from the gun fire a fine screen may be conveniently applied to the device by securing it to the peripheries of the external shoulder and the guard.

In the accompanying drawings:

Figure 1 shows in side view one of my recoil devices applied to a rifle barrel;

Figure 2 is a longitudinal section through the recoil device shown in Figure 1, a portion of the rifle barrel being shown in side view;

Figure 3 is an end view of the recoil device looking from right to left in Figure 2;

Figure 4 is a central longitudinal section through a recoil controlling device, the same as in Figure 2, except that the guard, instead of being integral with the device is shown as a separate part attached to the device;

Figure 5 is a view the same as Figure 4, but

showing the guard attached in a different manner.

Figure 6 is a view the same as in Figure 2, except that the guard is shown as a separate part;

Figure 7 is a view the same as in Figure 2, showing a recoil device in which the discharge ports are provided only on the top and sides of the device;

Figure 8 is a section on the line 8—8 of Figure 7;

Figure 9 is a longitudinal section through a recoil device, the same as in Figures 1 to 3, but having a fine mesh wire screen applied to eliminate flash, and

Figure 10 is a section on the line 10—10 of Figure 9.

Referring to Figures 1 to 3, inclusive of the drawings, A indicates my recoil device which is shown attached to the muzzle end of a rifle barrel 1; 2 indicates the wooden stock of the rifle, 3 indicates a bayonet attaching part, 4 a link through which the rest strap of the rifle is adapted to pass, and 5 indicates the front sight of the rifle.

The recoil device A is shown in Figures 1 to 3, attached to the muzzle end of the rifle barrel. This device, made in one piece, comprises a cylindrical part 10 having a radial flange 18 at its rear end and joined at its forward end to a 30 conical part 8 which has a cylindrical extension 8^a at its apex. The body has a gas chamber therein, indicated generally by the reference letter 9. The cylindrical portion 10 of the body has a cylindrical bore 13 extending inwardly from its 35 rear end adapted to receive the muzzle end of the rifle, this bore constituting the inlet end of the chamber, and the forward part of the bore constituting a part of the chamber. As shown, the end portion of the rifle barrel has external 40 threads 6 adapted to engage corresponding threads 10 in the wall of the bore 13, so that the device can be threaded on to the barrel. The barrel extends only part way into the bore 13 and the part of the bore in front of the barrel constitutes part of the chamber. A seal port 11 extends from the chamber through the cylindrical extension 8^a in axial alignment with the bore 13 and also with the bore of the rifle when the device is fitted thereon.

A shoulder 15 extends laterally from the inner end of the seal port to the side wall of the chamber, which wall slopes rearwardly and outwardly from the periphery of the shoulder 15

to an annular shoulder 14 which connects the forward portion of the part 18 with the rearward end of the conical part 8 of the body. A circular series of discharge ports 12 extend from the chamber through the shoulder 14, these ports being in line with the shoulder 15 and having their outer peripheries substantially in line with the periphery of the shoulder 15.

In operation when the gun is fired, the bullet 10 passes through the chamber and into and through the seal port, and as the chamber is relatively small, the gases and still burning products of combustion entering the chamber create an extremely high pressure therein, and these gases discharge through the rearwardly and outwardly directed ports against the atmosphere and react against the internal shoulder 15 at the forward end of the chamber, greatly eliminating recoil. In order to prevent these 15 rearwardly and outwardly directed gases and products of combustion from interfering with the operator of the gun, the radial flange 18 is provided on the rear end of the device, this flange constituting a guard for that purpose and 20 projecting outward far enough to prevent the products of combustion from being driven off parallel with the gun barrel, but not far enough to be in line with the outwardly inclined discharge ports.

30 In Figure 4 the recoil device is the same as in the previously described figures except that the guard 22 is a separate part, threaded onto the body, instead of being integral therewith. In Figure 5 the guard is the same as in the previous figures, except that the guard 23 is a separate part and swaged on to the body. Figure 35 6 is the same as Figure 2, except that the guard 26 is separate from the body and clamped between the body and the part 27 which supports the sight 5. The recoil device shown in Figures 40 7 and 8 is the same in all respects as the device shown in Figure 2, except that in the latter figure the discharge ports are arranged in a circular series, whereas in Figures 7 and 8 these ports 31 extend only around the top and sides 45 of the device, the lower part 32 of the body being free from such ports. This is of advantage where the operator of the rifle is shooting prone as there is no downward discharge of the gases 50 which might raise dust when the rifle barrel is close to the ground.

In Figures 9 and 10 a fine mesh wire screen 33 arranged in cylindrical form is secured at its edges to the peripheries of the guard 26 and shoulder 14 by suitable clamping rings 34 and 55 35 respectively. This screen may be used where it is desired to avoid flash.

I claim:

1. A recoil controlling device for guns adapted 60 to fire projectiles comprising a body having a gas chamber therein and having a cylindrical bore, adapted to receive the muzzle end of a gun barrel, extending inwardly from the rear end of said device, the forward part of said bore constituting part of said chamber, said device having a seal port at the forward end of said chamber in axial alignment with said bore and having an internal shoulder extending laterally from the inner end of the seal port to the side 65 wall of the chamber, the side wall of the chamber flaring rearwardly and outwardly from the periphery of said shoulder and closing the forward part of the chamber adjacent said shoulder against the lateral escape of gas, said device having a rearwardly facing external shoul- 70 der to the rear of the shoulder in the chamber and to the rear of the forward end of said cylindrical bore and having a plurality of discharge ports extending rearwardly and outwardly from said chamber, the outer peripheries of said ports being substantially in line with the periphery of said internal shoulder, and said ports extending through said external shoulder. 75

2. A recoil controlling device for guns adapted 10 to fire projectiles comprising a body having a gas chamber therein and having a cylindrical bore, adapted to receive the muzzle of a gun barrel, extending inwardly from the rear end of said device, the forward part of said bore constituting part of said chamber, said device having a seal port at the forward end of said chamber in axial alignment with said bore and having an internal shoulder extending laterally from the inner end of the seal port to the side wall of the chamber, the side wall of the chamber flaring rearwardly and outwardly from the periphery of said shoulder and closing the forward part of the chamber adjacent said shoulder against the lateral escape of gas, said device having a rearwardly facing external shoulder to the rear of the shoulder in the chamber and to the rear of the forward end of said cylindrical bore, and having a plurality of discharge ports extending rearwardly and outwardly from said chamber, the outer peripheries of said ports being substantially in line with the periphery of said internal shoulder and said ports extending through said external shoulder. 15

3. A recoil controlling device for guns adapted 20 to fire projectiles comprising a body having a gas chamber therein and having a cylindrical bore, adapted to receive the muzzle end of a gun barrel, extending inwardly from the rear end of said device, the forward part of said bore constituting part of said chamber, said device having a seal port at the forward end of said chamber in axial alignment with said bore and having an internal shoulder extending laterally from the inner end of the seal port to the side wall of the chamber, the side wall of the chamber flaring rearwardly and outwardly from the periphery of said shoulder and closing the forward part of the chamber adjacent said shoulder against the lateral escape of gas, said device having a rearwardly facing external shoulder to the rear of the shoulder in the chamber and to the rear of the forward end of said cylindrical bore, and having a plurality of discharge ports extending rearwardly and outwardly from said chamber, the outer peripheries of said ports being substantially in line with the periphery of said internal shoulder and said ports extending through said external shoulder, and an annular guard projecting radially outward from the rear end of said device. 30

4. A recoil controlling device for guns adapted 35 to fire projectiles comprising a body having a gas chamber therein and having a cylindrical bore, adapted to receive the muzzle end of a gun barrel, extending inwardly from the rear end of said device, the forward part of said bore constituting part of said chamber, said device having a seal port at the forward end of said chamber in axial alignment with said bore and having an internal shoulder extending laterally from the inner end of the seal port to the side wall of the chamber, the side wall of the chamber flaring rearwardly and outwardly from the periphery of said shoulder and closing the forward part of the chamber adjacent said shoulder against the lateral escape of gas, said device having a rearwardly facing external shoulder to the rear of the shoulder in the chamber and to the rear of the forward end of said cylindrical bore, and having an arcuate series of discharge ports 40 extending rearwardly and outwardly from said chamber, said ports being located at the top and sides of said device only, the outer peripheries of said ports being substantially in line with the periphery of said internal shoulder and said ports extending through said external shoulder. 45

5. A recoil controlling device for guns adapted 50 to fire projectiles comprising a body having a gas chamber therein and having a cylindrical bore, adapted to receive the muzzle end of a gun barrel, extending inwardly from the rear end of said device, the forward part of said bore constituting part of said chamber, said device having a seal port at the forward end of said chamber in axial alignment with said bore and having an internal shoulder extending laterally from the inner end of the seal port to the side wall of the chamber, the side wall of the chamber flaring rearwardly and outwardly from the periphery of said shoulder. 55

- 5 said shoulder and closing the forward part of the chamber adjacent said shoulder against the lateral escape of gas, said device having a rearwardly facing external shoulder to the rear of the shoulder in the chamber and to the rear of the forward end of said cylindrical bore, and having a plurality of discharge ports extending rearwardly and outwardly from said chamber, the outer peripheries of said ports being substantially in line with the periphery of said internal shoulder and said ports extending through said external shoulder, an annular guard projecting radially outward from the rear end of said device, and a fine mesh wire screen of cylindrical form secured to the margins of the guard and the exterior shoulder.
- 10 5. A recoil controlling device for guns adapted to fire projectiles comprising a body having a gas chamber therein and having a cylindrical bore, adapted to receive the muzzle end of a gun
- 15 barrel, extending inwardly from the rear end of said device, the forward part of said bore constituting part of said chamber, said device having a seal port at the forward end of said chamber in axial alignment with said bore and having an internal shoulder extending laterally from the inner end of the seal port to the side wall of the chamber, the side wall of the chamber flaring rearwardly and outwardly from the periphery of said shoulder and closing the forward part of the chamber adjacent said shoulder against the lateral escape of gas, said device having a rearwardly facing external shoulder to the rear of the shoulder in the chamber and to the rear of the forward end of said cylindrical bore and having a plurality of straight discharge ports extending rearwardly and outwardly from said chamber through said external shoulder, said ports being in line with said internal shoulder.
